UNITED STATES PATENT OFFICE.

ISAAC FRANCIS TAYLOR, OF EAST DULWICH, LONDON, ENGLAND, ASSIGNOR OF ONE-HALF TO SAMUEL PICK, OF LONDON, ENGLAND.

SHIP'S-BOAT HANDLING AND LAUNCHING APPARATUS.

1,292,145.

Specification of Letters Patent.

Patented Jan. 21, 1919.

Application filed May 19, 1916. Serial No. 98,645.

To all whom it may concern:

Be it known that ISAAC FRANCIS TAYLOR, a subject of the King of Great Britain and Ireland, residing at 5 Upland road, East Dulwich, London, England, has invented certain new and useful Improvements in or Connected with Ships'-Boat Handling and Launching Apparatus, of which the following is a specification.

10 This invention relates to apparatus for supporting boats on the boat deck of a ship and moving them across the deck when required to davits on either side of the ship and has for its object to provide apparatus 15 of simple construction that shall be easy of control and capable of operating under the most adverse conditions, as for example, when the ship has considerable list.

According to this invention the boats are 20 supported in rows one or more in height by means of chocks on pairs of flanged rails laid athwart the boat deck, the chocks being mounted to run on the rails and actuated by chains connected by ropes with winches arranged to actuate the chains or other means 25 to move the chocks in either direction on the rails. Means are also provided for holding the boats down in the chocks, consisting of traveling posts or uprights with hook-like yokes at their upper ends arranged to 30 engage over the gunwales of the boats and supporting and guide wheels at their lower ends which engage over and under the top flanges of the rails. Falls are also led from 35 barrels on the winches over the davits and also ropes for swinging the davits outboard or inboard, the winches employed being preferably of the type described in our prior specification No. 8590/14 40 with suitable auxiliary barrels mounted in the frames and geared with the actuating worm shaft.

The invention is hereinafter described with reference to the accompanying drawings in which:

Figures 1 and 2 illustrate conventionally in plan and elevation, boat handling apparatus constructed according to this invention.

Fig. 3 is an elevation of one of the davits suitable for use with the boat handling means shown in Figs. 1 and 2.

Figs. 4 and 5 are elevations at right angles of boat holding devices for retaining

the boats in position on the transporting track.

Figs. 6, 7 and 8 are detail views illustrating boat chocks in side elevation, end elevation and plan respectively.

As shown, the rails *a* are of I section and laid athwart the deck on arched chairs or supports *b* to which they are firmly secured. On the rails, chocks *c* are mounted to run on pairs of wheels *d*, said chocks comprising side plates or cheeks *c*¹ depending on opposite sides of the rail flange and carrying suitable seatings *c*² for the boat keels. The wheels *d* are mounted inside the chocks on bearing axles *e*, sufficient space being left between each pair of wheels for 70 the accommodation of a chain *f* or other means which is attached to a transverse distance bolt *g* secured between the side cheeks. The chocks are all coupled in like manner with the chain *f* which slides on the 75 top of the rail *a* and passes over pulleys *h* at the ends of the rail—Figs. 1 and 2—its opposite ends being connected to ropes *i* which are led under each rail in opposite directions, and over suitable pulleys *j* *j*¹ to 80 a winch barrel *k*, the chains of each pair of rails with their connected ropes forming one continuous flexible operating cable which when wound in either direction by an appropriate rotation of the winch barrel, will 85 actuate the chains of the adjacent rails and the boat chocks coupled therewith, causing the chocks with the boats *w* supported thereon to travel simultaneously in the required direction over their supporting rails. 90

As the chocks *c* with the boats *w* supported thereon reach in turn the launching position, the boats are lifted out of the chocks by the davits and as the loaded chocks are successively brought into the launching 95 position, the empty chocks in front of them are carried by the chain *f* over the ends of the rails *a* and supported in an inverted position underside the rails as shown in dotted lines in Fig. 2.

The boats *w* are maintained in position in the chocks by uprights or bars *l* having wheels *m* at their lower ends arranged to run above and below the flange of the rail, and yokes *n* at their upper ends adjustable in height and capable of engaging over the gunwales of the boats. These uprights are placed in position over the ends of the rails,

the upper flanges being suitably cut away to enable the lower wheels to be passed under the said flanges, and to set free the uprights when the boats are being run outboard.

5 The davits *o*, which are illustrated, are of the ordinary type, are swung outboard or inboard by ropes *p* wound in opposite directions on drums or pulleys *q* on the davit posts and also on a winch barrel *r*, while 10 the falls *s* are led over loose pulleys *t* mounted on the davit to rotate about the same axis and over other suitable guide pulleys *u* to the fall blocks *v*.

It will be seen that with the improved apparatus boats can be kept in the most convenient positions for launching by the davits and tackle from both sides of the ship, or 15 quickly transferred from one side of the

ship to the other. The boats may also be easily loaded while in position on the trolleys before being swung outboard and lowered.

What he claims and desires to secure by Letters Patent is:

A ship boat handling device including 25 flanged rails, wheeled boat carriages mounted thereupon, such boat carriages being connected together by means of an endless chain and means for holding the boats down in said boat carriages, such means comprising 30 uprights embracing the rail flanges at one of their ends and engaging the gunwales of the boat with their other end.

In testimony whereof he has affixed his signature.

ISAAC FRANCIS TAYLOR.

Copies of this patent may be obtained for five cents each, by addressing the "Commissioner of Patents, Washington, D. C."
